Primary Examiner — Barbara Fox*Assistant Examiner* — Mary Claire Ramirez(74) *Attorney, Agent, or Firm* — Fay Sharpe LLP(57) **CLAIM**

The ornamental design for agricultural flooring, as shown and described.

DESCRIPTION

FIG. 1 is a top perspective view of agricultural flooring showing my new design;

FIG. 2 is a bottom perspective view thereof;

FIG. 3 is a right side elevational view, the left side elevational view being a mirror image thereof;

FIG. 4 is a cross-sectional side elevational view taken from along line 4-4 in FIG. 1;

FIG. 5 is a cross-sectional side elevational view taken from along line 5-5 in FIG. 1;

FIG. 6 is a top plan view; and,

FIG. 7 is a bottom plan view.

The dash-dot-dash broken lines shown in the drawings depict the boundaries of the claim and form no part of the claimed design.

1 Claim, 7 Drawing Sheets(56)
